UNITED STATES PATENT OFFICE.

AARON M. SPRINGER AND REBECCA J. SPRINGER, OF PORTLAND, OREGON.

CLOTHES-DRYING RACK.

1,159,727.

Specification of Letters Patent.

Patented Nov. 9, 1915.

Application filed April 20, 1914. Serial No. 833,143.

To all whom it may concern:

Be it known that we, AARON M. SPRINGER and REBECCA J. SPRINGER, citizens of the United States, residing in the city of Portland, county of Multnomah, and State of Oregon, have invented certain new and useful Improvements in Clothes-Drying Racks, of which the following is a specification.

Our invention relates to clothes drying racks, and more particularly to certain improvements in portable clothes drying racks adapted to be folded up at will into small compass.

The primary object of our invention is to provide an extremely simple, light and inexpensive rack, and one which can be folded into the smallest possible space, and when opened up for use will stand alone and furnish a large number of bars on which to hang the clothes.

In order that others may thoroughly understand our invention we have shown one practical form thereof in the accompanying sheet of drawings which we will now describe.

Figure 1 is an end view of a rack set up ready for use; Fig. 2 is a side view thereof in folded condition; and Fig. 3 is an end view thereof in folded condition.

The rack as here illustrated comprises two main frames or members A and B, each composed of two upright end pieces as 1-1 and 2-2, respectively, and having cross or connecting bars 3-3 and 4-4 there-between as shown. Said frame members A and B are pivotally connected together so as to cross each other, as at 5-5, whereby they can be folded together, as shown in Figs. 2 and 3, or opened out, as shown in Fig. 1. Each of the frame members A and B is provided at its upper end with a second frame, as C and D, respectively, each second frame being composed of two end pieces as 6-6 and 7-7, respectively, connected by bars 8 and 9. Said second frames are pivotally connected at their meeting edges, by the members A and B, by means of a through rod or member 10, shown to be square in cross section between the pieces 7-7 and round at its end between the pieces 7-6. Said second frames are also pivotally connected to the main frame members A and B as at 11 and 12. One of the cross bars as 4' on the upper end of the member B is so placed as to be engaged by the frame member D when in open position, as shown in

Fig. 1 thereby preventing said members from further spread. Thus it will be seen that the frame members A and B and C and D are so pivoted together and their connecting cross bars are so placed that when said rack is folded as shown in Figs. 2 and 3, it occupies a space no thicker than the breadth of the members 1 and 2, plus the thickness of their cross bars 3 and 4, as shown in Fig. 3. In other words, the main frames A and B fold together into the same plane as do also the second frames C and D. It is also to be noted that when the rack is opened ready for use the cross bars are so positioned one above the other that clothes hanging upon one of said bars hang freely and out of vertical alinement with the other bars. In other words, each of the clothes-receiving bars is intended to occupy a separate vertical plane, or to be sufficiently above another, so that clothes hanging thereon will not interfere with another bar beneath it.

As one object of the invention is cheapness, without detracting from its usefulness and durability, the cross bars 3, 4, 7 and 8 are secured directly upon the edges of the members 1 and 2, 6 and 7, although it is evident that these might be inset in a manner well understood and need not be here illustrated.

We are aware, therefore, that slight changes can be made in the invention as here illustrated without departing from the spirit thereof, and we do not, therefore, limit the invention to the special showing here made, except as we may be limited by the hereto appended claims.

We claim,—

1. A clothes drying rack of the character described, comprising a pair of spaced upright end pieces with connecting bars there-between, a second pair of upright end pieces with connecting bars there-between, said second pair of end pieces being pivotally attached on the inner sides of the first end pieces, whereby to fold between the same, an inner top frame having its ends pivotally connected, respectively, to the inner sides of said second pair of end pieces near their tops, and an outer top frame having its ends pivotally connected to the outer sides of said first pair of end pieces near their tops, said inner top frame and outer top frame having at their upper ends a connecting rod common to both pairs, and adapted to fold above the ends of said first

and second upright end pieces, whereby said rack can be folded flat with all of its end pieces occupying the same plane.

2. A clothes drying rack of the character described, comprising an inner frame and an outer frame pivotally connected to fold together with all of their end pieces in exactly the same plane, a top inner frame pivotally connected within said inner frame adjacent its top, and a top outer frame having its end pieces pivotally connected to the outer sides of said outer frame adjacent its top, said top inner frame and top outer

frame being pivotally connected together at their tops, and adapted to fold above the ends of said inner and outer frames, whereby all of the end pieces of all of said frames fold into the same plane, substantially as described.

Signed at Portland, Multnomah county, 20 Oregon, this 14th day of April, 1914.

AARON M. SPRINGER.
REBECCA J. SPRINGER.
